UNITED STATES PATENT OFFICE

CHARLES ZEBROWSKI, OF WEST ALLIS, WISCONSIN

DOOR OPERATING MECHANISM

Application filed January 8, 1930. Serial No. 419,398.

This invention relates to new and useful improvements in door operating mechanism.

One of the objects of my invention is the provision of improved door operating mechanism which is particularly adapted for application to garage doors whereby the entrance doors to the garage may be opened without the necessity of the operator of the vehicle alighting to manually open the doors and includes means for closing the doors through movement of the vehicle after the vehicle has entered the garage.

Another object of my invention is the provision of door operating mechanism which includes means for maintaining the latching member in an inoperative position after the doors have been opened to admit the vehicle and also after the doors have been closed after the vehicle has entered the garage whereby the doors may be readily opened again when it is desired to remove the vehicle from the garage.

Another object of the present invention is the provision of door operating mechanism which includes means whereby to prevent unnecessary strain upon the doors after being moved to a closed position through the entrance of the vehicle to the garage if the vehicle should pass beyond a predetermined point necessary for closing the doors.

A still further object of the invention is the provision of door operating mechanism of the above character wherein the vehicle after entering the garage will maintain the door in a closed position until it is desired to remove the vehicle from the garage at which time the operating mechanism is actuated through the tension of a spring placed under tension by the entrance of the vehicle into the garage, so that as soon as the vehicle starts to move outwardly, the tension of this spring will actuate the mechanism and move the doors to an open position to allow the vehicle to pass from the garage.

With the above and other objects in view, the invention consists in the novel features of construction, the combination and arrangement of parts hereinafter more fully set forth, pointed out in the claims and shown in the accompanying drawings wherein:

Figure 1 is an elevation looking at the interior of a pair of doors, illustrating my improvement applied thereto;

Figure 2 is a top plan view of the operating mechanism;

Figure 3 is a transverse section through the garage looking toward the rear in the direction opposite that shown in Figure 1;

Figure 4 is a vertical sectional view on the line 4—4 of Figure 1;

Figure 5 is a detail section on the line 5—5 of Figure 2;

Figure 6 is a detail section illustrating the bumper to remove the strain from the closed doors if a vehicle passes beyond a predetermined point;

Figure 7 is a detail perspective view of the latch member which retains the door fastening member in an unlocked position.

Referring more particularly to the drawings, 1 indicates a garage which may be of the conventional type, having a pair of swinging doors 2 and 2' at the entrance end thereof with a smaller outlet door at the rear end of the garage.

This garage 1 may be of the well known metal type or of the ordinary wooden type, as the operation can be easily applied to practically any type of garage.

The operating mechanism includes a movable bar 4 which is longitudinally disposed lengthwise of the garage and slidably mounted within suitable guides 5, attached to the upper cross beams of the garage or any other suitable supports. Connected to the bar substantially midway its length is the cross member 6 and pivotally connected to opposite ends of the member 6 are the movable arms 7, the outer ends of which are pivotally connected to the inner side of the garage doors 2 and 2'. These arms 7 are preferably connected to the doors 2 and 2' at the upper cross bar of the doors, as shown in Figure 1, so as to form a substantially permanent connection and to eliminate the strain on the weakest part of the doors.

The outer end of the bar 4 is provided with an aperture 8, and adapted to be engaged in this aperture for the purpose of locking the bar 4 against longitudinal movement is

the upper end of the vertically movable rod 9. This rod 9 is slidably mounted within suitable guides 10 and 10' attached to the door 2.

5 The lower end of the rod 9 is pivotally connected to one end of a bell crank 11 which is pivotally mounted as at 12 upon a bracket 13 attached to the door 2. The other end of bell crank 11 is pivotally connected at 14 to the inner end of a slidable rod 15 provided with a bumper face or plate 16 at its outer end. This bumper plate 16 is used to be engaged by the vehicle for reciprocating the rod 15, the rod 15 imparting a rocking movement to bell crank 11 so as to exert a downward pull on rod 9 to disengage the upper end thereof from aperture 8.

20 Mounted upon the rod 9 is a coil spring 17 disposed between an adjustable nut 18 and bracket 10', whereby to serve as a bumper or shock absorber during the movement of the rod 9.

25 In order to maintain the rod 9 in an unlocked position while the doors are moved to a closed position after the vehicle has entered the garage, a pivoted latch 19 is mounted upon door 2 and is adapted to cooperate with serrations 20 on rod 9, as shown in Figure 1.

30 The latch 19 is normally urged toward the serrations 20 by means of a coil spring 21, one end of which is attached to the door 2 and the other end attached to the outer end of the latch.

35 Rotatably mounted upon one side wall of the garage adjacent the inner end thereof and supported by suitable brackets 22 is a rod 23 having attached to its lower end a U-shaped member 24, the intermediate or cross portion 25 of which normally extends outwardly from the side wall of the garage directly in the path of the vehicle, as it enters the garage whereby the usual forward bumper on the vehicle will strike the cross bar 25 for imparting a rotative movement to rod 23.

40 Extending laterally from rod 23 at the upper end thereof is a tubular arm 26 adapted to receive at its outer end the arm 27 on the coupling member 28. The arm 27 telescopes within arm 26 and is retained in various adjusted positions by means of set screw 29.

45 The coupling 28 is connected to the inner end of bar 4 by means of a link 30, one end of which is pivotally connected to the bar 4 and the other end pivotally connected to the rod 31. Coupling 28 is slidably mounted upon rod 31 which carries a coil spring 32 disposed between coupling 28 and an adjusting nut 33 on the outer end of rod 31.

50 The U-shaped member 24 and arm 26 are normally urged to the full line position, shown in Figure 2, or in other words, this arm 26 and member 24 are urged toward the doors 2 and 2', so that bar 4 will be moved forwardly

5 to the full line position shown in Figure 2, opening the doors when there is no pressure exerted against member 24. This operation is carried out through the medium of a heavy coil spring 34, one end of which is attached 70 to a joist or any other suitable stationary part of the building, while the other end is attached to arm 26.

75 In the operation of my improved device, the vehicle is moved forwardly until the bumper or any part of the front of the vehicle engages the plate 16 and pushes inwardly on rod 15 to regulate bell crank 11. This operation moves rod 19 downwardly, disengaging the upper end thereof from the aperture 8.

80 After the doors have been released, the vehicle is backed away slightly to allow the doors 2 and 2' to open. It will be noted that as soon as bar 4 is released, the tension of coil spring 34 will move bar 4 longitudinally so that the arms 7 will force the doors 2 and 2' to an opening position, as shown in Figure 2.

85 As soon as the doors have been moved to an open position, the vehicle is driven in to the garage until the front bumper thereof will engage with the cross bar 25 of the U-shaped member 24 and further continued movement of the vehicle will rotate the rod 23 which in turn will actuate arm 26 and move bar 4 longitudinally within guides 5 so as to pull the doors to a closed position.

90 At this point, I wish to call attention to the fact that when the vehicle engages the plate 16 and moves rod 9 downwardly, the spring actuated latch 19 will hold this rod down out of engagement with the aperture 8, the vehicle bearing against member 24 maintaining the doors in a closed position after the vehicle has been driven into the garage.

95 It will be noted that the coil spring 32 on rod 31 is of sufficient strength to permit the closing of the doors as soon as the vehicle engages members 24, but if the vehicle moves beyond, so that the operating members assume a position beyond that shown by the 100 dotted lines in Figure 2, the coupling member 28 will slide on rod 31 against the tension of spring 32 so as not to exert any extraordinary strain on the doors which would naturally have a tendency to disconnect arms 7 from the doors and destroy the usefulness of the mechanism.

105 Attention is directed to the fact that member 27 is adjustably mounted within arm 26 so that the coupling 28 may be adjusted to 110 various positions with respect to arm 26 whereby the outer end of rod 31 will strike the rear end of the garage, or will permit only sufficient movement of arm 26 for closing the doors, any further movement on the part of 115 arm 26 will be against the tension of spring 32.

120 It is fully believed that I have provided simple and inexpensive operating mechanism for garage doors which can be quickly and easily installed in an ordinary type of garage 125

whereby the doors may be quickly and easily opened without the driver of the vehicle alighting for opening the garage and where in the doors will be moved to a closed position after the vehicle has entered the garage, and will be maintained in a closed position until it is desired to move the vehicle from the garage.

In a great many garages, there is a possibility that there is no extra door such as shown at 3, and if this is the case, attention is directed to the fact that the arms 7 are pivotally connected to doors 2 and 2' by means of removable pins 35, whereby one of these pins may be quickly removed so that the door may be opened to allow for a person's exit at this point.

I claim:

1. In combination with a pair of swinging doors, movable means for locking said doors in a closed position, means having operative connection with the movable means and positioned upon the exterior of the doors for engagement by an object for releasing the locking means, a rotatable support spaced from the doors, an arm projecting from the upper end of the support, means forming connection between said arm and the doors, a projection at the lower end of the rotatable support and adapted to be positioned in the path of a moving object whereby the object striking said projection will rotate the rod and impart movement to the doors for moving them to a closed position, and means having operative connection with said arm for moving said doors to an open position upon release of the locking mechanism.

2. In combination with a pair of swinging doors, means for locking said doors in a closed position, means arranged upon the exterior of said doors, whereby to release said locking means, a rotatable member mounted at a point remote from the doors, a lateral arm at the upper end of said rotatable member, means forming operative connection between the outer end of said arm and said doors, a coil spring having one end connected to the arm and the other end connected to a stationary point whereby to impart a lateral movement to said arm for opening said doors upon release of the locking means, and a second lateral projection on the rotatable member beneath the arm adapted to be engaged by a moving object for closing said doors.

3. In combination with a movable door, releasably locking means for holding said door in a closed position, vehicle operated means disposed exteriorly of the door for releasing the locking means, a rotatable support arranged in spaced relation to the door, an arm projecting from said rotatable support, means operatively connecting said arm and door, a projection on said rotatable support and positioned in the path of a moving

object, whereby the object striking the projection will rotate the rod and impart closing movement to the door, and means operatively connected with said arm for moving the door to an open position upon release of said locking means.

In testimony that I claim the foregoing I have hereunto set my hand at Milwaukee, in the county of Milwaukee and State of Wisconsin.

CHARLES ZEBROWSKI.
